UNITED STATES PATENT OFFICE.

MINOR F. H. GOUVERNEUR, OF VICTOR, NEW YORK, ASSIGNOR TO LOCKE INSULATOR CORPORATION, OF BALTIMORE, MARYLAND, A CORPORATION OF MARYLAND.

INSULATOR.

Application filed September 8, 1921. Serial No. 499,172.

The invention relates to insulators, and more particularly to means for connecting insulators to supports or to other insulators.

The principal object of my invention, broadly stated, is to provide a novel form of metallic connecting device suitable for use with insulators, said connecting device being easy and simple to apply, possessing great strength, and involving but few parts. 10 Another object of my invention is to provide an inexpensive means for connecting ball strain insulators to guy ropes and to the insulating supporting towers, the said connecting devices being so constructed and arranged 15 as to permit the connection thereof by the line-men without the use of tools other than those usually carried by such men.

Another object of the invention is to provide a connecting device for insulators in 20 which the parts of the connector are so arranged that the greater the strain placed upon the coupling which joins the parts of the connector together the tighter this coupling becomes.

25 To these and other ends the invention relates to various elements and combinations of elements hereinafter set forth, the novel features whereof are pointed out in the claims.

In the drawings, wherein I have illustrated 30 several embodiments of the invention,—

Figure 1 is a view in side elevation of a ball strain insulator showing one form of my connector applied thereto.

Figure 2 is a vertical central section through 35 the ball strain insulator, one of the connecting devices being shown in elevation.

Figure 3 is a perspective view of the form of connector shown in Figs. 1 and 2.

Figure 4 is a horizontal transverse section 40 of Fig. 1.

Figure 5 is a view corresponding to Fig. 1, showing a slightly modified form of connector.

Figure 6 is a transverse vertical section of 45 Fig. 5.

Figure 7 is a perspective view of the form of connector illustrated in Figs. 5 and 6.

Figure 8 is a transverse horizontal section taken on line 8—8 of Fig. 6.

50 Figure 9 is a perspective view of a modified form of connector.

Throughout the specification and drawings

like parts are designated by like reference characters.

Referring first to Figs. 1 to 4, inclusive, the numeral 1 designates an insulator of the type commonly called a ball strain insulator. This type comprises a substantially rectangular body of porcelain or other dielectric material having projecting from the exterior surfaces thereof a plurality of ribs 2 the object of which is to increase the leakage distance over the surface of the insulator. Primarily these ball strain insulators are employed to insulate the guy ropes by which the tower or pole carrying the main conductor is supported, the ball strain insulator being interposed at some convenient point in the span between the anchor for the guy rope and the cable or tower.

While I have illustrated and described my connector in combination with a particular type of insulator, it is to be understood that I do not limit my invention to this type, since many other forms of insulator may be advantageously employed with the connector hereinafter set forth.

Piercing the insulator at points spaced from the opposite ends and extending at right angles to each other are a plurality of openings 3, 3, the adjacent edges of the openings being preferably curved as at 4 to provide a curved bearing surface. To connect the ball strain insulator to the tower as is generally done, and to the guy rope, I may provide a two-part connector 5 the portions 6 and 7 of which are preferably made of comparatively heavy and stiff galvanized wires 8. The wires 8 of each portion are bent or otherwise shaped into loop form and the end portions of each loop are then brought together and bent inwardly and rearwardly as shown at 9 and 10, respectively, to form hooks 11. The closed or looped end 12 of each portion is of such width as to receive the hooked portion 11 of the coacting part of the connector. Preferably the portion 6 of the connector is adapted to engage with a suitable connection in the guy rope or with the conductor support, as the case may be, and for this purpose it is provided with a bend or apex 13 substantially midway of its length. The portion 7 is preferably symmetrically curved so as to closely fit the curved portions 4 of the opening 3.

To assemble the device the hook 11 of the portion 6 is first interlocked with the loop 12 of the portion 7 as shown in Fig. 3. The loop 12 of the member 6 is then entered through a suitable member carried either by the tower or the guy rope, and then the hook 11 of the portion 7 is entered and passed through the opening 3 in the insulator. The loop 12 of the portion 6 is then forced over the hook 11 of the portion 7 and the parts are drawn into substantially the position shown in Fig. 2. From an inspection of this figure it will be observed that when the parts are in assembled position the bill of each hook 11 is in contact with the body portion of the insulator, and it will be apparent to those skilled in the art that upon strain being placed upon the connector the tendency of the parts is to crowd or force the bills of the respective hooks into intimate contact with the adjacent wires of the respective portions. It will thus be evident that the greater the strain placed upon the connector the tighter will the hooks close upon the coacting loops 12.

It might be here pointed out that the diameter of the openings in a ball strain insulator is limited and is generally three quarters of an inch in width, and with this diameter of opening in the insulator I preferably employ a wire 8 having a diameter of one quarter of an inch. Wire of this section has a maximum strength far in excess of that required under ordinary circumstances, and consequently with this size of wire there is a large margin of safety. It will be obvious, of course, that when the opening 3 has a diameter of three quarters of an inch the looped portions 12 which are spaced apart sufficiently to receive the bills of the respective hooks 11 will have a maximum diameter of at least one inch. As a result it is impossible to force the loops 12 of either portion 6 or 7 through the opening in the insulator. This difficulty is obviated by forming the hooked portions with a maximum diameter of three quarters of an inch measured over the hook, thus permitting the hooks 11 to freely enter the openings 3 in the insulator body. This form of hook is rendered possible since the bills of the hooks need only be spaced from the main body a distance sufficient to receive a single width of the wire.

While the construction described above is of great importance and is one of the features of my invention, I do not wish to be limited to either the exact diameter of wire or of the noted diameter of the openings in the insulator, since the size of the openings and the size of the wire may be varied through a wide range without departing from the spirit of my invention.

Referring now to Figs. 5 to 8, inclusive, wherein I have shown but a single member 14 constituting the connector, it will be observed that this member is also formed of compara-

tively heavy and stiff galvanized wire and may be applied to the insulator by projecting the hooked end 15 thereof through the opening 3 and then continuing the threading of the connector until the loop 16 is substantially 70 in the position shown in Fig. 6. The hook 15 is then engaged with the loop 16 and the wire bent or shaped to form an apex 17, whereupon the connection is made. It will, of course, be understood that prior to the connection of the hook and loop 15 and 16, respectively, the connector 14 will be passed through the coacting part either on a guy rope or tower, as the case may be. In this form also, owing to the position of the bill of the hook 15 and its engagement with the body of the insulator it will be obvious that the greater the strain placed upon the connector the greater will be the gripping action of the hook upon the loop 16. 75 80 85

In Fig. 9 I have shown a substitute for the wire in the form of a galvanized cable 18. Preferably I form a hook 19 at the open end of the cable, the said hook being produced by bending the ends of the cable inwardly and rearwardly upon itself and by suitably connecting to the adjacent ends a sleeve or metal covering 20. A convenient way of connecting the sleeve 20 to the cable is to solder the same in place, the solder being forced into the opening through which the strands of the cable extend so as to intimately connect the cable to the sleeve. The method of associating the connector shown in this modification with the insulator is identical with that already described with reference to Figs. 5 to 8, inclusive, and need not be further commented on. In this instance, however, after the parts are interlocked I preferably solder or otherwise suitably connect the adjacent portion of the main body of the connector or cable 18 to the portion 20 so as to obviate slipping of the hook 19 which might be caused by the flexibility of the cable. 90 95 100 105

It will be noted that in each instance there is provided a wide bearing area due to the engagement of two strands of wire in the insulator, and it will also be obvious that whether the device is of the multiple form or of the single unit type, a self locking feature 110 is utilized to prevent accidental disengagement of the parts under strain. 115

I claim:

1. The combination with an insulator element having an opening therein, of a metallic connector passing through said opening, said connector having a hook and eye engagement between parts thereof, the bill of said hook being interposed between the insulator and a portion of said connector to prevent the accidental disengagement thereof. 120 125
2. The combination with an insulator of the strain type having a plurality of passages therethrough, of a metallic connector comprising a pair of semi-flexible members each 130

furnished with a closed eye at one end and a hook at the opposite end, the bills of said hooks being adapted to engage the body of the insulator to prevent the disengagement 5 thereof.

3. A demountable insulator combination comprising an insulator having transverse passages near opposite ends and at angles to each other, an attaching link comprising 10 hinged legs one of which passes through one of said passages and is adapted to fasten to the other leg after having been passed through said passage of the insulator, the other of said passages being formed to pass

through said link when the link is closed on 15 the insulator, said last named passage and said link being adapted to have wires and the like fastened therethrough.

4. In combination, an insulator having a passage therethrough and a link comprising 20 two hingedly connected members, one of said members having an end portion adapted to be removably positioned in said passage and project therethrough for detachable and 25 immovable engagement with the end of the other member.

In testimony whereof I affix my signature.
MINOR F. H. GOUVERNEUR.
